WOVEN NARROW FABRIC

John A. Drake, Fairfield, Conn., assignor to The American Fabrics Company, Bridgeport, Conn., a corporation

Application February 26, 1959, Serial No. 54,756

Term of patent 3½ years

(Cl. D92—1)

The figure is a plan view of the woven narrow fabric showing my new design.

The drawing is shaded to show color contrast rather than any specific color.

I claim:

The ornamental design for a woven narrow fabric, substantially as shown and described.
